US0D1059584S

(12) **United States Design Patent** (10) **Patent No.:** **US D1,059,584 S**
(45) **Date of Patent:** **** Jan. 28, 2025**

(54) **BREATHING MASK ASSEMBLY INCLUDING A FRAME AND SEAL**

(71) Applicant: **Fisher & Paykel Healthcare Limited**, Auckland (NZ)

(72) Inventors: **Andrew Grant Niccol**, Auckland (NZ); **Neil Gray Duthie**, Auckland (NZ); **Erik Robertus Scheirlinck**, Auckland (NZ)

(73) Assignee: **Fisher & Paykel Healthcare Limited**, Auckland (NZ)

(**) Term: **15 Years**

(21) Appl. No.: **29/892,929**

(22) Filed: **May 23, 2023**

Related U.S. Application Data

(62) Division of application No. 29/727,653, filed on Mar. 12, 2020, now Pat. No. Des. 1,010,103, which is a division of application No. 29/564,637, filed on May 13, 2016, now Pat. No. Des. 882,066.

(57) **CLAIM**

The ornamental design for a breathing mask assembly including a frame and seal, as shown and described.

DESCRIPTION

FIG. 1 is a top perspective view showing the breathing mask assembly including a frame and seal showing our new design;

FIG. 2 is a left side view thereof;

FIG. 3 is a front view thereof;

FIG. 4 is a right side view thereof;

FIG. 5 is a rear view thereof;

FIG. 6 is a top view thereof; and,

FIG. 7 is a bottom view thereof.

Where utilized, the broken lines show portions of the breathing mask assembly including a frame and seal that form no part of the claimed design.

1 Claim, 4 Drawing Sheets
